UNITED STATES PATENT OFFICE.

HERSCHEL V. HARRELD, OF HEDRICK, IOWA.

DEVICE FOR DRYING CORN.

Application filed January 20, 1925. Serial No. 3,611.

To all whom it may concern:

Be it known that I, HERSCHEL V. HARRELD, a citizen of the United States, residing at Hedrick, in the county of Wapello 5 and State of Iowa, have invented a new and useful Device for Drying Corn, of which the following is a specification.

This invention relates to a seed corn drying device of a collapsible type.

10 The object of the invention is to provide a drier of this character constructed so as to provide maximum ear supporting means while affording ample air space and ventilation for the corn.

15 Another object is to provide a device of this character with self-locking means for holding the hanger in rigid position when loaded and which requires no frame for supporting it.

20 Another object is to provide a collapsible hanger or drier of this character which may be placed in a very small space when not in use.

25 With the foregoing and other objects in view which will appear as the description proceeds, the invention resides in the combination and arrangement of parts and in the details of construction hereinafter described and claimed, it being understood 30 that changes in the precise embodiment of the invention herein disclosed may be made within the scope of what is claimed without departing from the spirit of the invention.

In the accompanying drawings:

35 Figure 1 represents a front elevation of a portion of a drier constructed in accordance with this invention with corn ears shown mounted thereon;

40 Fig. 2 is a similar view of the drier collapsed ready for storing or shipping;

Fig. 3 is a top plan view of the device; and

Fig. 4 is a detail transverse section.

The drier rack constituting this invention 45 is made in the form of a lazy-tong structure composed of a plurality of metal bars 1 and 2 which are of the same length and are pivotally connected with each other intermediate their ends as shown at 3. Any desired number of these bars may be employed and each bar 2 is pivotally connected at its rear end with the front end of bar 1 as shown at 4 while the rear end of bar 1 is pivotally connected with the front end of the 50 bar 2 below it as shown at 5. The projecting front ends 6 of the bars 1 and 2 extend

beyond their pivotal connection with the other bars and are pointed to form prongs or spurs for penetrating the base of the ears of corn, to be mounted thereon, said ears being shown at E in Fig. 1.

This lazy-tong structure when opened for use as shown in Fig. 1 has the bars which constitute it pivotally connected with each other and arranged at right angles to each other so that when the spurs or penetrating ends 6 enter the bases of the ears of corn, said bases will rest flat against said bars which assist in supporting the ear and permit a comparatively short prong to be used. 70 When so arranged the base of one ear sets back under the other so that said ears may be placed in close relation and yet have sufficient air space between them as is shown clearly in Fig. 1.

A self-locking device for the rack or drier is provided in the form of two links 7 and 8 which are pivotally connected at their lower or rear ends with the two uppermost bars 1 and 2 as shown at 10 and at their other ends are equipped with overlying heads 11 and 12 which are pivotally connected at their centers as shown at 13. The head 11 has a peripheral notch or recess 14 formed therein while head 12 has a laterally extending lug 15 struck out from the periphery which extends into the recess 14 and by engagement with one of the end walls of the recess 14 limits the opening position of the bars as is shown clearly in Fig. 1. This 90 connection of the heads 11 and 12 forms a self-locking device for the hanger and holds the bars in rigid position when opened to their full extent.

This arrangement of the bars 1 and 2 with the self-locking links 7 and 8 connected therewith provides a rack which requires no frame for supporting it thus greatly reducing the cost of production and rendering the drier much lighter.

100 This arrangement of pivotally connected bars 1 and 2 also provides an open space 16 through the center of the drier which operates as a flue for affording a free circulation of air between the ears of corn.

When in use this drier or hanger may be suspended from a rod or other suitable support so that there will be ample ventilation of the corn and it may be made of any desired size being preferably constructed to accommodate twenty ears.

110 When not in use the hanger is collapsed as

shown in Fig. 2, the bars 1 and 2 folding flat against each other and occupying a minimum amount of space providing a flat device which may be stored or shipped in 5 numbers, one arranged over the other, and occupy a very small space.

I claim:—

In a corn drier, a lazy-tong construction comprising a plurality of pivotally connected bars, said bars having outer pointed

extremities extended beyond the pivot points of the adjacent bars, the adjacent bars providing stops for the corn positioned on the pointed extremities, and a stop to prevent movement of the bars past their operative 15 position in their operative positions.

In testimony that I claim the foregoing as my own, I have hereto affixed my signature.

HERSCHEL V. HARRELD.
